CLAIM

The ornamental design for a foldable carrying case, as shown and described.

DESCRIPTION

FIG. 1 is a rear elevational view of a foldable carrying case showing my new design in an unfolded position; FIG. 2 is a front elevational view thereof;

FIG. 3 is a front perspective view thereof in a partially unfolded position;

FIG. 4 is a top plan view in an unfolded position;

FIG. 5 is a bottom plan view thereof;

FIG. 6 is a left end elevational view thereof;

FIG. 7 is a right end elevational view thereof;

FIG. 8 is a side perspective view in a folded position; and,

FIG. 9 is an opposite side perspective view thereof.

FIG. 1

FIG. 2
